UNITED STATES PATENT OFFICE.

DANIEL J. O'ROURKE, OF CLAREMONT, NEW HAMPSHIRE, ASSIGNEE TO SULLIVAN MACHINERY COMPANY, OF CLAREMONT, NEW HAMPSHIRE, A CORPORATION OF MAINE.

TAPPET VALVE-MOTION FOR DIRECT-ACTING ENGINES.

No. 892,297.

Specification of Letters Patent.

Patented June 30, 1908.

Application filed April 8, 1904. Serial No. 202,167.

To all whom it may concern:

Be it known that I, DANIEL J. O'ROURKE, a citizen of the United States, residing at Claremont, in the county of Sullivan and 5 State of New Hampshire, have invented an Improvement in Tappet Valve-Motions for Direct-Acting Engines, of which the following description, in connection with the accompanying drawings, is a specification, like 10 letters on the drawings representing like parts.

My invention consists of improvements in tappet valves, being particularly applicable to tappet valve motions employed upon direct acting engines, such for example as are 15 used with rock-drilling machines.

My invention will be best understood by reference to the following description when taken in connection with the accompanying 20 illustration of one specific embodiment thereof, submitted for illustrative purposes wholly, while its scope will be more particularly pointed out in the appended claims.

In the drawings, Figure 1 shows one form 25 of my invention applied to a compressed air rock drill, the cylinder of the latter being partially broken away, and together with the valve, being shown in longitudinal section; Fig. 2 represents the same parts shown in 30 Fig. 1, with the valve and piston in a slightly different position, and Fig. 3 is a section taken through the engine at the tappet valve.

Referring to the drawings, *a* represents the cylinder of a direct acting engine employed 35 in connection with the rock drill, the piston therefor being shown at *b*, and the air chest at *c*. The compressed air enters the air chest, *c*, from the source of supply not shown, through an appropriate air inlet, *d*, and is 40 controlled in its passage to the opposite ends of the cylinder, *a*, by the slide valve, *e*, of ordinary construction.

To effect suitable control of the slide valve, *e*, there are provided upon the piston, *b*, appropriately shaped inclined surfaces, *f*, *f'*, which are adapted, during the reciprocation of the piston, alternately to engage the opposite ends of the slideable segmental valve actuator, *g*, the latter being provided with an upwardly projecting tooth-engaging portion entering the inner face of the slide valve, *e*, and

contacting on either side with suitable and preferably tooth-shaped engaging surfaces to impart a movement to the valve corresponding to the reciprocating movement of the 55 piston. The valve and the segment may be provided with any desired number of any engaging teeth, although for simplicity I prefer in practice to employ the single tooth shown upon the segment, and the surfaces of these 60 teeth may be shaped either accurately to give correct rolling contact between the engaging surfaces, or with any desired degree of approximation.

To provide suitable guide-ways for the 65 sliding segment *g*, I may and preferably do form a portion, *h*, in the walls of the cylinder in the shape of an arc to afford appropriately shaped inner guide walls for the segment, the outer or upper guide walls of the segmental 70 groove being formed by the material of the valve plate, *i*, secured to the cylinder and so shaped as to enter appropriately formed recesses therein.

The construction illustrated wherein the 75 segmental guide walls are formed partly by the cylinder and partly by the valve plate, provides an accurate and efficient guide-way for the segments, and yet increases greatly the simplicity of construction, since the removal of the valve plate from the engine cylinder leaves the segment, *g*, unattached to any part and free to be withdrawn. The provision of the inner guide-way, *h*, is superior and preferable to those constructions 80 where the cylinder is entirely cut away to receive the tappet member since it materially strengthens the cylinder at that point.

I have here shown the slide valve, *e*, as provided with a suitable balance plate, *j*, spring- 90 pressed by the spring, *k*, against the back of the valve, *e*, tending to reduce the load upon the valve and the friction impeding its movement.

In Fig. 1, the valve, *e*, is shown in its central position where no air can be admitted to either end of the cylinder. To start the engine in operation when the valve is in this position, the piston is first moved off center in one direction or the other to throw the 10 valve away from its central position, as for example, to the left of the position shown in

Fig. 1, and to that shown in Fig. 2. Air then passes from the air chest under the valve and into the port, *l*, passing to the left hand end of the cylinder as viewed in the drawings, 5 causing the piston to travel right-handedly until the incline *f'* strikes the depressed end of the segment, whereupon the upward sliding movement of the latter forces the valve to the right opening the opposite port, *m*, to the air chest, and the port, *l*, to the chamber, 10 *o*, through which the exhaust passes through an appropriate outlet impinging upon the tooth of the segmental valve actuator *g* and tending to force the same in the direction of 15 the passage of the exhaust. The piston thus started in operation, obviously maintains its reciprocatory movement as long as desired.

The segment and its guides are preferably so shaped as to bring the center of oscillation 20 on the opposite side of the path of travel of the reciprocating piston walls which engage the segment ends, the center of oscillation in the engine illustrated practically intersecting the axis of the piston. This relation between the segment, its center of oscillation 25 and the tappet surfaces, *f*, *f'* permits a very quick initial movement to be given to the valve and eliminates much unnecessary friction at the engaging surfaces as compared 30 with prior tappet members pinned or pivoted to oscillate about an axis outside the cylinder walls.

By the provision of a sliding segment directly engaging the walls of the slide valve 35 itself without the interposition of connecting links, journal members or the like, there is produced a tappet motion reduced to but two operative moving parts adapted to transmit directly to the valve the reciprocatory movement 40 of the piston, which transmission, inasmuch as the same is through the instrumentality of the segmental gear alone, may be made as accurate and correct as desired by properly shaping the engaging toothed surfaces. 45 The toothed segment, *g*, requires no additional fastening device other than the simple coöperating guiding walls of the cylinder and the valve plate, and is therefore readily removable although being at all 50 times accurately and effectively controlled in its movements. This construction also provides in a very simple manner, means for bringing the center of segment oscillation within the cylinder walls.

It is to be understood that my invention is 55 not restricted to the mere details of construction, and form and arrangement of parts herein presented, the same being submitted for illustrative purposes only, but that the 60 same may be widely modified without departing from the spirit thereof.

Claim—

1. The combination with a cylinder, a piston 65 therein, a valve plate, and a sliding valve controlling ports which open into the cylin-

der at the opposite ends of the piston, said piston having oppositely arranged tappets, the wall of the cylinder having a segmental groove or channel formed therein and disposed longitudinally of the piston, a segmental valve actuator seated in said segmental groove of the cylinder wall with its ends projecting into the path of movement of the tappets on the piston, the inner face of said valve plate having a segmental groove or 70 channel therein, whereby the said plate may be seated upon said segmental valve actuator, the latter being guided in its movement between the cylinder wall and said valve plate, and said actuator having a tooth in engagement with the sliding valve to reciprocate 75 the latter.

2. The combination with a cylinder, a piston therein, a valve plate, and a sliding valve controlling ports which open into the cylinder at the opposite ends of the piston, said piston having oppositely arranged tappets, the wall of the cylinder having a segmental groove or channel formed therein and disposed longitudinally of the piston, a segmental valve actuator seated in said segmental groove in the cylinder wall with its ends projecting into the path of movement of the tappets on the piston, the inner face of said valve plate having a segmental groove or 80 channel therein, whereby the said plate may be seated upon said segmental valve actuator, the latter being guided in its movement between the cylinder wall and said valve plate, and said actuator having a tooth in engagement with the sliding valve to reciprocate 85 the latter.

3. The combination with a cylinder, a piston therein, a valve plate, and a sliding valve controlling ports which open into the cylinder at the opposite ends of the piston, said piston having oppositely arranged tappets, the wall of the cylinder having a segmental groove or channel formed therein and disposed longitudinally of the piston, a segmental valve actuator seated in said segmental groove in the cylinder wall with its ends projecting into the path of movement of the tappets on the piston, the inner face of said valve plate having a segmental groove or 90 channel therein, whereby the said plate may be seated upon said segmental valve actuator, the latter being guided in its movement between the cylinder wall and said valve plate, said segmental groove or channel in the inner face of the valve plate being enlarged to 95 form a chamber through which the exhaust may pass to a suitable outlet, said actuator having a tooth in engagement with the sliding valve to reciprocate the latter.

100

3. The combination with a cylinder, a piston therein, a valve plate, and a sliding valve controlling ports which open into the cylinder at the opposite ends of the piston, said piston having oppositely arranged tappets, the wall of the cylinder having a segmental groove or channel formed therein and disposed longitudinally of the piston, a segmental valve actuator seated in said segmental groove in the cylinder wall with its ends projecting into the path of movement of the tappets on the piston, the inner face of said valve plate having a segmental groove or 105 channel therein, whereby the said plate may be seated upon said segmental valve actuator, the latter being guided in its movement between the cylinder wall and said valve plate, said segmental groove or channel in the inner face of the valve plate being enlarged to form a chamber through which the exhaust may 110 pass to a suitable outlet, said actuator having a tooth in engagement with the sliding valve to reciprocate the latter.

115

3. The combination with a cylinder, a piston therein, a valve plate, and a sliding valve controlling ports which open into the cylinder at the opposite ends of the piston, said piston having oppositely arranged tappets, the wall of the cylinder having a segmental groove or channel formed therein and disposed longitudinally of the piston, a segmental valve actuator seated in said segmental groove in the cylinder wall with its ends projecting into the path of movement of the tappets on the piston, the inner face of said valve plate having a segmental groove or 120 channel therein, whereby the said plate may be seated upon said segmental valve actuator, the latter being guided in its movement between the cylinder wall and said valve plate, said segmental groove or channel in the inner face of the valve plate being enlarged to form a chamber through which the exhaust may 125 pass to a suitable outlet, said actuator having a tooth in engagement with the sliding valve to reciprocate the latter, the said tooth being seated in said chamber, whereby the exhaust may impinge directly thereon.

130

4. The combination with a cylinder, a piston therein, a valve plate, and a sliding valve controlling ports which open into the cylinder at the opposite ends of the piston, said piston having oppositely arranged tappets, said valve plate having a chamber formed therein in communication with the exhaust, the wall of said chamber being provided with a segmental groove or channel, a segmental valve actuator seated in said segmental groove or channel and contacting with the walls thereof and having a sliding valve engaging tappet extending into said chamber and adapted to be impinged upon by the exhaust, the main or body portion of said valve actuator being shielded from the impact of the exhaust by the wall of said groove or channel.

5. A drill of the character described comprising a casing provided with a cylinder, a slide valve controlling the motive power entering said cylinder, a piston working in said cylinder, and a slidably supported rocker provided with an integral arm engaging said valve, and against which arm the exhaust impinges to hold the rocker against movement until the piston completes its stroke.

6. A drill of the character described comprising a casing provided with a cylinder, a piston working in said cylinder, a valve seating carried by said casing, a slidably supported rocker provided with an integral arm against which the exhaust impinges to hold the rocker against movement until the piston completes its stroke, and a slide valve engaged by the free end of said arm.

7. A drill of the character described comprising a casing provided with a cylinder, a piston working in said cylinder, a valve seating carried by said casing, a slide valve controlling the motive power entering said cylinder, and a slidably mounted rocker having an integral arm connected to said valve, said arm being located in a recess in the valve seating forming a part of the exhaust outlet, whereby the exhaust will impinge thereagainst to hold the rocker against movement until the piston completes its stroke.

8. A drill of the character described comprising a casing provided with a cylinder, a piston working in said cylinder, a valve seating having a chamber therein forming part of the exhaust outlet, a slidably mounted rocker having an arm extended into said chamber, and against which the exhaust impinges to hold said rocker against movement until the piston completes its stroke, said rocker being also provided with arms for engaging the piston, and a slide valve controlling the motive power entering said cylinder, said valve being connected to the first mentioned arm of said rocker.

9. A drill of the character described comprising a casing provided with a cylinder, said casing having an exhaust outlet, a piston

working therein and provided with an annular reduced portion forming shoulders, a slidably mounted rocker having curved arms for engaging the shoulders on said piston, said rocker having a vertical member located in said exhaust outlet, and against which the exhaust impinges to hold said rocker against movement until the piston completes its stroke, and a slide valve connected to said vertical member and controlling the motive power entering said cylinder.

10. The combination with a cylinder, a piston therein, a valve plate, and a sliding valve controlling ports which open into the cylinder at the opposite ends of the piston, said piston having oppositely arranged tappets, the wall of the cylinder having a segmental groove or channel formed therein and disposed longitudinally of the piston, a segmental valve actuator seated in said segmental groove of the cylinder wall with its ends projecting into the path of movement of the tappets on the piston, the inner face of said valve plate having a segmental groove or channel therein, whereby the said plate may be seated upon said segmental valve actuator, the latter being guided in its movement between the cylinder wall and said valve plate, and an outturned toothed valve actuating arm carried by said actuator and engaging a correspondingly shaped recess in the inner face of said slide valve, said toothed arm and said recess being properly shaped to afford rolling contact between the same and thereby to reduce the friction between the said valve and the said arm.

11. The combination with a cylinder, a piston therein, a valve plate, and a sliding valve controlling ports which open into the cylinder at the opposite ends of the piston, said piston having oppositely arranged tappets, the wall of the cylinder having a segmental groove or channel formed therein and disposed longitudinally of the piston, a segmental valve actuator seated in said segmental groove of the cylinder wall with its ends projecting into the path of movement of the tappets on the piston, the inner face of said valve plate having a segmental groove or channel therein, whereby the said plate may be seated upon said segmental valve actuator, the latter being guided in its movement between the cylinder wall and said valve plate, and means between the valve and the actuator for causing movement of the former through the movement of the latter, said means comprising a toothed arm secured to one member and a correspondingly shaped recess formed upon the other member, said toothed arm and recess being so shaped as to provide for rolling contact between the same, thereby to reduce the friction to a minimum.

12. In an apparatus of the class described, the combination with the cylinder *a*, the

piston *b*, the valve plate *i*, the valve *e* controlling ports to the cylinder, the cylinder walls having a guiding portion *h*, tappets *f*, *f'* upon the piston, the slidale segmental 5 rocker *g* having toothed engagement with the valve *e* and working in the space or chamber *o*.

In testimony whereof, I have signed my name to this specification, in the presence of two subscribing witnesses.

DANIEL J. O'ROURKE.
